Facility and convenience of the invention is to provide a device for fastening sheet metal sections to a building structure in such a manner as to substantially obviate the sections becoming loose due to rain, wind and the like.

UNITED STATES PATENT OFFICE

2,574,937

DEVICE FOR FASTENING METAL ROOF TO BUILDINGS

William E. Sampson, LeQuire, Okla.

Application October 22, 1947, Serial No. 781,262

2 Claims. (Cl. 108—13)

1

This invention appertains to novel and useful improvements in devices for fastening sheet metal sections to a building or providing a roof thereon.

An object of this invention is to efficaciously clamp roof sections on a building structure in such a manner as to substantially obviate the sections becoming loose due to rain, wind and the like.

Another object of this invention is to provide means for carrying out the above mentioned function.

Another purpose of this invention is to provide improved clamping means engageable with the flanges of sheet roofing which project to the interior of a building.

Another purpose of this invention is to provide a device of the nature to be described which is extremely simple, inexpensive and easily manufactured.

Other objects and features of novelty will become apparent to those skilled in the art, in following the description of the illustrated preferred embodiment of the present invention, illustrated in the accompanying drawings, wherein:

Figure 1 is a fragmentary perspective view of a roof utilizing the present invention;

Figure 2 is a perspective view of the roof and building framing utilized beneath the roofing disclosed in Figure 1;

Figure 3 is an enlarged sectional view of a joint utilizing the present invention;

Figure 4 is a sectional view of a modified form of the present invention, showing the same utilized in conjunction with a channel iron;

Figure 5 is a sectional view of another form of the present invention;

Figure 6 is a longitudinal sectional view of the invention shown in Figure 5 and taken on the line 6—6 thereof and in the direction of the arrows;

Figure 7 is a sectional view of a further modification of the inventive concept;

Figure 8 illustrates another use of the present invention;

Figure 9 illustrates the invention shown in Figure 5, showing the same in a different position of operation; and,

Figure 10 is a sectional view of the housing sections joined;

Figure 11 is a sectional view of a detail of construction showing an alternate element utilized with and forming a portion of the invention.

Referring now in detail to the illustrated preferred embodiments of the present invention, like characters of reference are used throughout to indicate similar elements thereof.

This invention has been developed to provide a

device for the purpose of efficaciously sealing a barn, animal house, etc. from the weather. Heretofore metallic roof tops were applied to such structures by means of nails, driving the nails directly through the exposed surface of the roof sections and into the wood structural members. The necessary consequence followed; wind entered the building and gradually lifted the roof a small amount until the roof sections rattled and even blew off in times of storms.

It is well known that after a short time, the roof sections which are secured to a building structure through the utility of nails, become loose to such an extent as to permit water to seep around the nails and undesirably enter the building structure.

Noting Figure 1 it is seen that no nails are required in the attachment of the sections to a building structure. More important, there are no nails extending through the upper surface of the roof sections whereby rain water and the like may penetrate the roof. It will be seen further that fastening means project from the upper surfaces of each roof section, to a point below predetermined structural members for anchoring purposes.

A building structure 10 is provided with a plurality of purlins 12 and 14 respectively which are secured to the truss members 16 and 18 respectively by any suitable conventional means. The said strips 12 and 14 are spaced a fixed predetermined distance across for a purpose to be described hereinafter.

Sheets of metallic roofing 20 are provided with a flange 22 having a doubled back portion 24 operatively associated therewith.

Of course, sheets of roofing material 20 are placed in side by side relation and a housing 26 is attached to a single sheet and the next adjacent sheet. The said housing is preferably somewhat elliptical in cross sectional appearance and has a flange 28 on each inner portion thereof. The said flanges 28 are positioned in the above described flange 22 and the utility of the turned down portion 24 is now apparent.

It is to be noted at this point that there is disclosed a roof utilizing sheets of material having the general wavey configuration. However, this invention may be utilized in conjunction with many types of sheet roofing with equal effectiveness. The said housing 26 has bowed portions 30 therein which may serve the purpose of a resilient clip when fixed to sheets of roof material.

The said housing 26 may be placed in progressive rotation relative to each other for effecting greater length. A terminal portion of the housing 26 is undercut a small amount, re-

moving a portion of the bowed portion 30 and the flanges 22. The resulting tongue 31 on the upper part of the housing 26 then becomes somewhat resilient due to the inherent properties of the metal. The next adjacent housing may then be simply slipped under the tongue 31 as shown in Figure 10. This forms a lap joint substantially weather resistant connection.

A specially designed clip is used in attaching the sheets of roofing to the building structure seen in Figure 2. A plate 32 having slots 34 and 36 therein is provided with an externally threaded shank 38. An aperture is provided in the said shank 38 and a wing nut 40 with an associated washer 42 is adapted to be positioned on the said externally threaded shank. As is readily apparent from an inspection of Figure 9 the plate 32 is inserted between the purlins 12 and 14, thence between the space remaining between the adjacent roof sections 20. The slots 34 and 36 are engaged by the flanges 22 of the said roof sections 20 and then, a wing nut with its associated washers placed on the said shank. By tightening the said wing nut the roof may efficaciously be pulled toward the purlins thereby tightly locking the roof to the building structure. Of course, the aperture mentioned above may be utilized for the purpose of locking the wing nut in place or may serve a second purpose to be described subsequently.

Going now to Figure 4 there is disclosed another embodiment of this invention, the distinguishing feature being only in the application of a clip 44 on the shank. The aforementioned aperture is obviated in this embodiment. As is readily apparent from an inspection of Figure 4 this type of clamping means may be utilized in conjunction with metallic structures having channels 46 therein, eye beams, angles and the like.

The clip 44 has a folded portion 45 lockingly engageable with the flange of an eye beam or the like. An aperture is supplied in the clip and the shank extends therethrough. Of course, a nut and associated washer may be used to hold the clip in place.

Noting now Figure 3 it is readily apparent that a slightly modified device is utilized in securing the terminal portions of the roof sections at the apex of the said roof structure 10. A bracing strip 48 is supplied adjacent the apex of the said building structure 10. The plate 50 of the said fastening means is somewhat similar to the plate 32 described above. The slots 52 therein are supplied at an angle relative to the shank 54 of the fastening means, as opposed to a substantially parallel slot 34 and 36. Suitable securing means such as a nut 56 and an associated washer is supplied on the said shank.

Reference is now made to Figure 11 wherein there is disclosed the use of a modified form of the crown securing means. In place of the bracing strip 48 there is used a metallic anchor member 57 having properly inclined faces for firm seating and securing purposes.

It will be noted that the housing or crown portion 58 supplied on the said roofing sheets 20 is somewhat different from that housing utilized along the longitudinal axes of the said plane of the roof. The difference is quite evident in that the flanges are lacking.

Going now to an embodiment of the invention disclosed in Figure 6, it will be noted that the plate 32 is supplied with the shank 38 accompanied by the aperture 60 mentioned in conjunction with the embodiment of the invention

shown in Figure 9. This aperture may be utilized for extending a cotter pin or the like therethrough or if desired, may be utilized for receiving a nail 62 extending therethrough. For this construction reference is made primarily to Figure 8.

While there has been described and illustrated but preferred embodiments of the present invention, it is apparent that variations may be made herein without departing from the spirit of the invention. Accordingly, limitation is sought only in accordance with the scope of the following claims.

Having described the invention, what is claimed as new is:

15. 1. In a roof construction which includes sheets of roofing having upwardly extending downwardly opening channel-shaped flanges at adjacent edges thereof, said flanges opening on said sheets the improvement which comprises; means for fastening flanges and said sheets of roofing in fixed spaced position with respect to each other comprising a housing disposed over said upturned flanges, said housing having upturned edges extending interiorly of said housing and disposed in said channel-shaped flanges, a plate disposed in said housing and having slots therein, said housing edges and said flanges being disposed in said slots so that said channel-shaped flanges are clamped on said roofing edges,
- 20 30 a shank extending from said plate and outwardly of said housing, and means carried by said shank adjustably disposed thereon for clamping a roof component therebetween and the sheets of roofing.
- 35 2. In a roof construction which includes sheets of roofing having upwardly extending downwardly opening channel-shaped flanges at adjacent edges thereof, said flanges opening on said sheets the improvement which comprises; means for fastening flanges and said sheets of roofing in fixed spaced position with respect to each other comprising a housing disposed over said upturned flanges, said housing having upturned edges extending interiorly of said housing and disposed in said channel-shaped flanges, a plate disposed in said housing and having slots therein, said housing edges and said flanges being disposed in said slots so that said channel-shaped flanges are clamped on said roofing edges,
- 40 45 a shank extending from said plate and outwardly of said housing, and means carried by said shank adjustably disposed thereon for clamping a roof component therebetween and the sheets of roofing,
- 50 55 2. In a roof construction which includes sheets of roofing having upwardly extending downwardly opening channel-shaped flanges at adjacent edges thereof, said flanges opening on said sheets the improvement which comprises; means for fastening flanges and said sheets of roofing in fixed spaced position with respect to each other comprising a housing disposed over said upturned flanges, said housing having upturned edges extending interiorly of said housing and disposed in said channel-shaped flanges, a plate disposed in said housing and having slots therein, said housing edges and said flanges being disposed in said slots so that said channel-shaped flanges are clamped on said roofing edges, a shank extending from said plate and outwardly of said housing, and means carried by said shank adjustably disposed thereon for clamping a roof component therebetween and the sheets of roofing, and locking means removably carried by said shank in selected positions thereon for preventing the foregoing means from loosening.

WILLIAM E. SAMPSON.
